Jacob Beesley, of Philadelphia, Pa.
Assignor to
Jno. S. Clark & Washington Harris, of same place.
Letters Patent No. 1005, dated May 11, 1858.

The schedule referred to in these Letters Patent, and making part of the same.

To all whom it may concern:

Be it known, that I, Jacob Beesley of the City of Philadelphia, in the County of Philadelphia, and State of Pennsylvania have invented a new and original design for Stove doors and I do hereby declare that the following is an exact description of the same reference being had to the accompanying drawings.

b' show the molding in section. I claim the ornamental design as combined and shown in the specification & drawings.

Witnessed,

Jacob B. Coats. 3
